TONJES A. BOTH, OF STRATFORD, CONNECTICUT, ASSIGNOR TO THE CONNECTICUT ELECTRIC MANUFACTURING COMPANY, OF BRIDGEPORT, CONNECTICUT, A CORPORATION OF CONNECTICUT.

ELECTRIC CANDLE SOCKET.

Application filed July 26, 1921. Serial No. 487,649.

This invention relates to an electric fitting and especially to a candle socket, and has for an object to provide an improved structure for fittings of this type in which it will be unnecessary to pass the lead wires through the side walls of the conduit. It is a further object of the invention to provide a fixture of this type which will have comparatively few parts, which may be easily assembled, and which when assembled will be strong, and not likely to get out of order. With these and other objects in view I have devised the improved device illustrated in the accompanying drawings in which;

Fig. 1 is a side elevation of my improved candle socket with a portion of the casing broken away to disclose the interior thereof;

Fig. 2, a longitudinal central sectional view of the socket with the casing removed;

Fig. 3, an exploded view showing the various elements in perspective; and

Fig. 4 is a plan view of the fixture complete.

Reference numeral 10 indicates the exterior shell or casing which is constructed of some non-conducting material such as fibre. The lower end of this shell is closed by the lower insulating block 11, this block having an annular rib 12 on its upper surface adapted to fit in the end of the shell or casing. The block 11 is provided with a central opening 13 through which extends a nipple 14, this nipple having threaded engagement with the upper end of the conduit 15 and is secured against turning thereon by means of a set screw 16. This nipple 14 is provided with shoulders 17 upon which corresponding shoulders in the opening 13 of the block 11 rest. The shoulders 17 are formed by milling off two sides adjacent the junction of the upper and lower cylindrical portions as shown in the lower part of Fig. 3, which operation also leaves two flat sides. The upper portion of opening 13 in the block 11 is also flattened on two sides to fit this portion of the nipple and to prevent turning of the nipple in the block. On the upper end of the block, the rib 12 forms two recesses 18 and 19 separated by the tongues 20. These recesses are adapted to receive the lower segmental end portions 21 and 22 of the binding post brackets 23 and 24 respectively. After these segmental ends are placed within the recesses, a fibre collar or

washer 25 is placed upon the upper surface 55 thereof. A second metal washer 26 is placed upon the top of washer 25 and the whole is secured together by spinning over the upper end of the nipple 14 as shown at 27. Because of the tongues 20 separating the ends of segmental portions 21 and 22 and the fact that the inner diameter of these portions is larger than the diameter of the upper half of the nipple, a space 28 is left between these elements as shown in Fig. 2 and, therefore, no 60 insulating washer is required at this point. 65

A second insulating block 29 is secured to the upper ends of the binding post brackets 23 and 24 by suitable screws 30' and 30 respectively, the body portions of the binding post brackets providing means for holding these blocks separated a sufficient distance to take out the ends of the leads 31 from the upper end of the nipple 14 and to allow these ends to be bent over the edge and 70 fastened thereto by binding screws 32. The upper block 29 is provided with a radially extending recess 33 leading at one end to a longitudinal channel 34 in one side of the block, and at the other end to a longitudinal 75 opening 35 extending through the center of the block 29. The recess 33 and channel 34 are adapted to receive the central contact spring 36, the lower end of which is bent around over the lower end of the block 29, 80 is secured between this block and the upper end of binding post bracket 24 and in contact therewith by means of the screw 30. To the upper end of the block 29 is secured the threaded shell or socket 37 for the usual 85 threaded lamp base. This shell is provided at its lower end with an inwardly extending flange 38 through which screws 30' extend. These screws pass through the block 29 and are threaded at their lower ends in the upper section 23' of the binding post bracket 23. If desired, washers 39 may be provided under the heads of screws 30'. It will be 90 apparent that these screws form an electrical connection between the binding post bracket 23 and the threaded shell or socket 37. 95

In assembling, the upper end of the central contact spring 36 may be bent upwardly to the dotted line position shown in Fig. 2 and then the lead wires 31 inserted with their ends extending through the opening 35 as also shown in dotted lines in Fig. 2. The 100 whole fixture may now be screwed on to the 105

end of the conduit 15 without twisting the lead wires 31. After it has been screwed into position the ends of the wires 31 may be drawn downwardly from the opening 35 and bent outwardly and secured under the heads of the binding screws 32 in the usual manner. The spring 36 is then bent downwardly into the full line position in Fig. 2 which is the normal working position. The shell 10 is applied by screwing it down over the threaded socket 37 as it is provided with threads to fit the outer surface of those on the socket.

It will be clear from the foregoing that I have devised a simple and rigid structure which is easy to assemble and easily applied to the end of the conduit and also that it is not necessary to lead the wires 31 out through the side walls of this conduit. Furthermore, at no point are these wires outside the fixture where they would be liable to injury but are at all times within the confine of the insulated blocks and binding post brackets.

Having thus set forth the nature of my invention, what I claim is:

1. A conduit fitting comprising an insulating block, a nipple extending through and attached to the block, means for securing the nipple to the conduit, binding posts secured to the block by said nipple on the opposite side of the block from the conduit, said block being arranged to allow the lead wires from the conduit to extend therethrough to the binding posts, a second insulating block carried by said binding posts and spaced from the first block, and lamp contacts carried by the second block and having electrical connection with the binding posts.

2. A conduit fitting comprising an insulating block having a longitudinal opening therethrough, a nipple secured to the block, means for securing the nipple to a conduit, binding posts secured to the block by said nipple, a second insulating block secured to the binding posts, lamp contacts carried by the second block and having electrical connection with the binding posts, and lead wires extending from the conduit through the opening in the block to the binding posts.

3. A conduit fitting comprising an insulating block having a longitudinal opening therethrough, a tubular nipple extending through said opening, means for securing

the nipple to a conduit, means for securing the nipple to the block, binding posts secured to the block by said nipple on the opposite side from the conduit, and lead wires extending from the conduit through the nipple to the binding posts.

4. In a device of the class described, an insulating block provided with a longitudinal opening therethrough, a tubular nipple extending through said opening, means for securing the nipple to a conduit, spaced binding posts on the opposite side of the block provided with inturned flanges resting against the block, an insulating washer resting upon said flanges and clamped thereagainst by the spun over end of the nipple, and lead wires passing through the nipple from the conduit to the binding posts.

5. In a device of the class described, an insulating block provided with recesses at one end separated by tongues integral with the block, an oblong opening extending through the block and communicating with said recesses, a tubular nipple shaped to substantially fit said opening, means for securing said nipple to a conduit, binding post brackets having inturned segmental portions resting in said recesses, means for securing the brackets to the block, and lead wires passing through the nipple from the conduit to the brackets.

6. An electrical fitting comprising spaced insulating blocks having aligned openings therethrough, binding post brackets between the blocks and secured to the same to maintain them in spaced relation, a tubular nipple secured to one of the blocks, means for securing the nipple to a conduit, lamp terminals carried by the other block and connected with said brackets, and lead wires extending from the conduit through the first block to the brackets.

7. In an electrical fixture, longitudinally spaced insulating blocks, binding post brackets between the blocks and provided with flanges at one end, a tubular nipple extending through one of the blocks and having an inner end adapted to be spun over said flanges to secure the binding posts to said block, means for securing the tube to a conduit, and lamp terminals carried by the other block and having electrical connection with said binding post brackets.

In testimony whereof I affix my signature.

TONJES A. BOTH.
